UNITED STATES PATENT OFFICE.

EDWARD W. STEIMER, OF DUBOIS, PENNSYLVANIA.

DESIGN FOR A DEVICE FOR FASTENING CLOTHES-LINES.

46,326.

Specification for Design.

Patented Aug. 25, 1914.

Application filed June 24, 1914. Serial No. 847,127. Term of patent 7 years.

To all whom it may concern:

Be it known that I, EDWARD W. STEIMER, a citizen of the United States, residing at Dubois, in the county of Clearfield and State of Pennsylvania, have invented a new, original, and ornamental Design for a Device for Fastening Clothes-Lines, of which the following is a specification, reference being had to the accompanying drawing, forming part thereof.

Figure 1 is a side view of a device for fastening clothes lines embodying my new design. Fig. 2 is a face view thereof.

I claim:

The ornamental design for a device for fastening clothes lines, as shown.

EDWARD W. STEIMER.

Witnesses:

ROBERT MACLATCHIE,
CHAS. PITZER.
